UNITED STATES PATENT OFFICE.

CHARLES E. RIEDEL, OF DETROIT, MICHIGAN, ASSIGNOR TO DETROIT SCALE MANUFACTURING COMPANY, OF DETROIT, MICHIGAN, A CORPORATION OF MICHIGAN.

DESIGN FOR A SCALE-CASING.

49,781.

Specification for Design.

Patented Oct. 17, 1916.

Application filed July 28, 1916. Serial No. 111,948. Term of patent 14 years.

To all whom it may concern:

Be it known that I, CHARLES E. RIEDEL, a citizen of the United States, residing at Detroit, in the county of Wayne and State of Michigan, have invented a new, original, and ornamental Design for a Scale-Casing, of which the following is a specification, reference being had to the accompanying drawings, forming a part thereof.

In the drawings, Figures 1 and 2 are re-

spectively side and rear views of a scale casing, showing my new design.

I claim—

The ornamental design for a scale casing, as shown.

CHARLES E. RIEDEL.
